D9/565; 215/379, 381-383; 220/660, 669;
222/321.9, 372, 385

The ornamental design for a part of bottle, as shown and described.

DESCRIPTION

See application file for complete search history.

(56) **References Cited**

FIG. 1 is a top, front and side perspective view of a part of bottle showing our new design;

FIG. 2 is a front elevational view thereof;

FIG. 3 is a rear elevational view thereof;

FIG. 4 is a side elevational view thereof;

FIG. 5 is an elevational view of the other side thereof;

FIG. 6 is a top plan view thereof; and,

FIG. 7 is a bottom plan view thereof.

The broken lines immediately adjacent the shaded areas represent the bounds of the claimed design while all other broken lines represent environment and are for illustrative purposes only; the broken lines form no part of the claimed design.
